ADJUSTABLE DISPENSING CLOSURE

Alex Limbach, Carmel, N. Y.

Continuation of application Serial No. 560,567,
October 27, 1944. This application February
28, 1951, Serial No. 213,228

16 Claims. (Cl. 299—89)

1

This application is a continuation of my application Serial No. 560,567, filed October 27, 1944, now abandoned.

This invention relates to an improved one-hand operated adjustable dispensing closure for containers of liquid which is desired to be dispensed. Such a dispenser may constitute a permanent part of the container, the contents of which are to be discharged by the dispenser and may be permanently assembled with the container at the time that the contents of the latter are introduced into the container and constitutes the closure for the container or may be screwed onto the neck of the container in the conventional manner of a bottle closure.

An object of this invention is a closure dispenser made up of a few parts of simple construction and which is easy and inexpensive to manufacture but operates in a highly efficient manner.

In one embodiment of the invention, a disk of flexible material having an aperture supports a tube adapted to extend into a container with one face of the disk contacting the end of the container neck. A cup has its outer bottom face provided with an aperture in alignment with the flexible disk aperture. The cup bottom inner face is slightly concave except for a narrow rim portion and a strip of flexible material overlies the bottom inner face. The flexible strip is of less width than the diameter of the concave portion and is of proper length and end configuration to conform to the inner surface of the cup wall. A rigid washer overlies said flexible strip and snugly fits the inner surface of the cup wall. A hemispherical bulb has an annular rim resting on the rigid washer with its periphery engaging the inner wall of the cup and a circular band encloses and clamps the aforementioned members in assembled relation. The rigid washer is chamfered at its periphery to form a pair of annular chambers and grooves in both faces of the rigid washer extend between its center aperture and said annular chambers. A circular recess formed in the inner surface of the cup wall communicates with both said annular chambers and an aperture leads from said recess through said cup to the exterior thereof. The circular band is provided with an opening in radial alignment with the cup wall aperture.

Compression of the bulb depresses the flexible strip downwardly into position to seal the aperture through the cup bottom and forces the bulb contents through the rigid washer grooves into the annular chambers and from there into the cup recess from which the contents are dis-

2

charged through the cup wall aperture and band opening. Upon expansion of the bulb, air is drawn thereinto by way of the band opening and cup aperture, the annular chambers and the rigid washer grooves while liquid is drawn from the container through the cup-bottom aperture between the straight edges of the flexible strip and the concave portion of the cup bottom into an annular chamber from whence it passes through grooves in one face of the washer to its central aperture and thence into the interior of the bulb.

Other objects, novel features and advantages of this invention will become apparent from the following specification and accompanying drawings, wherein:

Fig. 1 is an elevation of the upper end of the container equipped with a dispensing closure embodying the invention;

20 Fig. 2 is a section on the line 2—2 of Fig. 1;
Fig. 3 is a section on the line 3—3 of Fig. 2;
Fig. 4 is a section on the line 4—4 of Fig. 2;
Fig. 5 is a section on the line 5—5 of Fig. 2;
Fig. 6 is an enlarged fragmentary view similar
25 to Fig. 1 partially broken away, and

Fig. 7 is an enlarged fragmentary section through the cup wall substantially on the line 7—7 of Fig. 3.

30 A disk 10 of rubber or other suitable gasket-forming material is provided with a central boss 11 through which extends a cylindrical passageway 12 of two different diameters. In the portion of larger diameter is received the end of a tube 13 of glass or other suitable material. The end of the passageway 12 opposite the tube 13
35 terminates in a conical recess 14. In the face of the disk opposite the boss 11 there is provided a circular groove 15 having radial extensions 16, the groove 15 and its extensions being initially formed of rectangular cross-section as indicated
40 by the dot-dash line of Fig. 6. A passageway 17 leads from the groove 15 through the disk 10.

45 A cup 18 of rigid material such, for example, as metal and of the same diameter as the disk 10 rests on said disk and the cup bottom is provided with an offset conical apertured portion 19 seated in the recess 14 with the opposed conical surfaces in air-tight sealing relation. The cup bottom inner face is slightly concave except for a narrow rim portion 20 which is flat and the bottom outer face may be correspondingly convex. In the commercial embodiment of the invention, the extent of concavity is less than is shown in the drawings, wherein it is necessary
55 to exaggerate the extent of concavity for the

sake of clarity. A strip 21 of thin suitable flexible material and of less width than the concave portion of the cup bottom overlies said cup bottom and is of proper length and end configuration to coincide with the inner periphery of the cup wall 18a. A disk 22 of suitable rigid material such, for example, as metal overlies the flexible strip 21 and is of proper diameter snugly to fit the inner surface of the cup wall. A substantially semispherical bulb 23 of rubber or other suitable material has an annular flange 24 resting on the washer 22 with its periphery engaging the inner surface of the cup wall. An annular band 25 surrounds the peripheries of the disk 10 and the cup 18 and the flange 24 with one edge of the band being inturned over the flange 24. The band 25 also is inturned at 26 into contact with the bottom surface of the disk 10 to clamp the bulb 23, washer 22, flexible strip 21, cup 18 and flexible disk 10 in the assembled relation shown in Fig. 2. The remaining edge of the band is turned over a flange 27 on the neck 28 of a container for clamping the dispensing device to the container with the tube 13 projecting substantially to the bottom of the container.

The periphery of the disk 22 is chamfered at 29 and 30 to form two separate annular chambers 31 and 32. A circular recess 33 is formed in the inner surface of the cup wall 18a of proper size to communicate with both the chambers 31 and 32 and an aperture 34 leads therefrom through the cup wall. The washer 22 has grooves 35 and 35a in its top and bottom faces leading from its central opening 36 to the periphery of the washer and into communication with the chambers 31 and 32. Each of the grooves 35 and 35a is arranged substantially tangentially of the aperture 36 and communicates with the annular chambers 31 and 32 at an out-of-normal angularity. The band 25 is slightly offset outwardly at 37 adjacent the cup wall aperture 34 and is provided with an opening 38 in alignment with said aperture 34.

In the operation of the dispenser above described, compression of the bulb 23 depresses the flexible strip 21 downwardly into sealing contact with the concave inner surface of the cup bottom so as to prevent flow of the bulb contents through the tube 13 into the container and forces the bulb contents through the grooves 35 and 35a to the chambers 31 and 32 and from said chambers into the recess 33 from which said contents are discharged through the aperture 34 and opening 38. Upon expansion of the bulb 23, the flexible strip 21 is drawn into sealing contact with the bottom of the washer 22 and out of contact with the concave bottom surface of the cup thereby providing passageways as shown in Figs. 2 and 7 at 21a between the straight edges of the strip 21 and the inner concave surface of the cup bottom. Air is drawn into the bulb by way of the opening 38, aperture 34, chambers 31 and 32 and grooves 35 and 35a while liquid is drawn from the container through the tube 13 and the passageways 21a into the chamber 31 and thence through the grooves 35 into the opening 36 of the washer 22 and finally into the interior of the bulb. The contents of the bulb thus comprise both air and liquid which is dispensed in highly dispersed condition through the orifice 34 and opening 38. The arrangement of the grooves 35 and 35a is such that the direction of flow of air and liquid through the chamber 31 is opposite to the direction of flow of air and liquid through the chamber 32 so that when the two streams

reach the recess 33 they are caused to circulate around therein in the same direction as illustrated in Fig. 6, whereby thorough mixture of the air and liquid is effected within the recess prior to discharge thereof through the aperture 34 and opening 38 in a highly dispersed condition.

The grooves 15 and 16 in conjunction with the aperture 38 provide for passage of air into or out of the container to maintain atmospheric pressure therein. The peripheries of the disk 10 and the cup bottom outer surface are chamfered to form an annular chamber 39 communicating with the interior of the offset portion 37 of the band 25. Air may thus flow from the exterior of the container into the interior of the container through the opening 38, chamber 39, grooves 16 and 15 and aperture 17. Air may flow from the interior of the container to the exterior thereof by the reverse route. The grooves 15 and 16 are of a cross-section designed to prevent them becoming blocked when the disk 10 is pressed against the bottom of the cup 18 by the offset portion 37 of the band 25. Customarily, grooves of flexible material have been of semi-circular cross-section and under pressure the flexible material is displaced into the grooves to such extent as completely to block them. In the present construction, such block is avoided by making the grooves 15 and 16 initially of rectangular cross-section. When the disk 10 is compressed against the cup 18, the grooves 15 and 16 are converted from their initial rectangular cross-section into the cross-section illustrated in Fig. 6. The material of the flexible disk is still distorted into the grooves but in such a manner as to leave open channels 16a providing communication between the groove 15 and the chamber 39.

In the structure above described, the various units may be assembled without requirement of any particular orientation of one unit with respect to any other except that the opening 38 of the band 25 must be in alignment with the aperture 34 in the wall of the cup 18. Assembly is effected merely by placing the members in assembled relation irrespective of any orientation thereby effecting speedier assembly with consequent production cost reduction. The dispenser may be attached to the bottle neck otherwise than by clamping as shown. For example, the bottle neck may be threaded and the lower portion of the band 25 may be correspondingly threaded to permit attachment of the dispenser to the bottle neck by screwing one to the other. Various degrees of dispersion and volume may be obtained by changing the size of the cup wall aperture 34 as well as by changing the width of the flexible member 21 thereby varying the ratio of the air and liquid as well as the amounts thereof drawn into the bulb 23 upon expansion thereof. Also, variation of the width of the strip 21 effects variation in the clearances around the straight edge of said strip so as to vary the undulating movement of this strip. Thus, by proper selection of dimensions, the above-described structure may be adapted to meet all desired quality and quantity performance of liquid dispenser.

In order to facilitate illustration of the above-described structure, the disk 10 has been shown in the position in which one end of the groove 16 communicates directly with the interior of the offset portion 37. However, the operation of the device is the same with the disk oriented so that the ends of the groove 16 communicate with the

chamber 39 at points removed from the offset portion 37. Also, while it is preferred to have the annular chamber 32 as well as the annular chamber 31, it is to be understood that the chamber 32 may be dispensed with in which event the chamber 31 along will serve as above described to accomplish the ejection of the bulb contents and the introduction of air and liquid thereinto.

What is claimed is:

1. In an atomizer comprising a cup having a fluid inlet aperture in its bottom and an outlet opening in its side wall, a thin flexible member in the cup over the inlet aperture, a washer over the flexible member, and an air bulb over the washer, the combination of an annular chamber between the inner surface of the wall of the cup and the peripheral edge of the washer extending completely around the entire periphery of the cup wall and communicating with the outlet opening therein, a fluid passageway interconnecting the interior of the bulb and said annular chamber, and a fluid passage bounded on one side by the bottom of the cup and on the other by the flexible member and washer and leading under an edge of the flexible member, said last named passage interconnecting said inlet aperture and said annular chamber.

2. In an atomizer comprising a cup having a fluid inlet aperture in its bottom and an outlet opening in its side wall, a thin flexible member in the cup over the inlet aperture, a washer over the flexible member, and an air bulb over the washer, the combination of a bevel extending completely around one peripheral edge of the washer and defining with the inner surface of the wall of the cup an annular chamber communicating with the outlet opening, grooves in the washer defining a passageway between the interior of the bulb and said annular chamber, the flexible member being a strip having a length and end configuration conforming to the inner surface of the side wall and a width less than the diameter of the side wall whereby there is defined a fluid passage bounded on one side by the bottom of the cup and on the other by the flexible member and washer and leading under an edge of the flexible member, said passage interconnecting said inlet aperture and said annular chamber.

3. A dispensing closure comprising a cup having a central bottom aperture, said cup having its bottom inner face slightly concave, a flexible strip overlying said cup bottom, said strip being of less width than the diameter of said concave portion and being of proper length and end configuration to conform to the inner surface of the cup wall, a rigid disk overlying said flexible strip and having a central aperture, a hemispherical bulb having its rim resting on said disk with its periphery contacting the inner surface of the cup wall, means clamping the aforementioned members in assembled relation, said rigid disk being shaped at its periphery to form an annular chamber, at least one groove in the surface of said rigid disk facing said flexible member and extending between the central aperture of the disk and said annular chamber, and an aperture in said cup wall communicating with said chamber.

4. A dispensing closure comprising a cup having a central bottom aperture, said cup having its bottom inner face slightly concave, a flexible strip overlying said cup bottom, said strip being of less width than the diameter of said concave

portion and being of proper length and end configuration to conform to the inner surface of the cup wall, a rigid disk overlying said flexible strip and having a central aperture, a hemispherical bulb having its rim resting on said disk with its periphery contacting the inner surface of the cup wall, an apertured circular band enclosing and clamping the aforementioned members in assembled relation, said disk being shaped at its periphery to form an annular chamber, at least one groove in the surface of said disk facing said flexible strip and extending between the central aperture of said disk and said annular chamber, and an aperture through said cup wall communicating with said chamber and being in alignment with said band aperture.

5. A dispensing closure comprising a cup having a central bottom aperture, said cup having its bottom inner face slightly concave, a flexible strip overlying said cup bottom, said strip being of less width than the diameter of said concave portion and being of proper length and end configuration to conform to the inner surface of the cup wall, a rigid disk overlying said flexible strip and having a central aperture, a hemispherical bulb having its rim resting on said disk with its periphery contacting the inner surface of the cup wall, an apertured circular band enclosing and clamping the aforementioned members in assembled relation, said disk being chamfered at its periphery to form a pair of annular chambers, grooves in both faces of said disk extending between its central aperture and said annular chambers, a recess in the inner surface of the cup wall communicating with both said chambers, and an aperture leading from said recess through said cup wall in alignment with said band aperture.

6. A dispensing closure comprising a disk of flexible material having an aperture, a cup having its bottom outer face contacting said flexible disk and having a bottom aperture alined with said flexible disk aperture, said cup having its bottom inner face slightly concave, a flexible strip overlying said bottom inner face, said strip being of less width than said concave portion and being of proper length and end configuration to conform to the inner surface of said cup wall, a rigid disk overlying said flexible strip and having a central aperture, a hemispherical bulb having its rim resting on said rigid disk with its periphery engaging the inner surface of said cup wall, means clamping the aforementioned members in assembled relation, said rigid disk being shaped at its periphery to form an annular chamber, at least one groove in the surface of said rigid disk facing said flexible member and extending between the central aperture of the disk and said annular chamber, and an aperture in said cup wall communicating with said chamber.

7. A dispensing closure comprising a disk of flexible material having an aperture, a cup having its bottom outer face contacting said flexible disk and having a bottom aperture alined with said flexible disk aperture, said cup having its bottom inner face slightly concave, a flexible strip overlying said bottom inner face, said strip being of less width than said concave portion and being of proper length and end configuration to conform to the inner surface of said cup wall, a rigid disk overlying said flexible strip and having a central aperture, a hemispherical bulb having its rim resting on said rigid disk with its periphery engaging the inner surface of said cup wall, an apertured circular band enclosing and clamp-

ing the aforementioned members in assembled relation, said rigid disk being chamfered at its periphery to form a pair of annular chambers, grooves in both faces of said rigid disk extending between its central aperture and said annular chambers, a recess in the inner surface of said cup wall communicating with both said chambers, and an aperture leading from said recess through said cup wall in alinement with said band aperture.

8. A dispensing closure comprising a disk of flexible material having an aperture, a cup having its bottom outer face contacting said flexible disk and having a bottom aperture alined with said flexible disk aperture, said cup having its bottom inner face slightly concave, a flexible strip overlying said bottom inner face, said strip being of less width than said concave portion and being of proper length and end configuration to conform to the inner surface of said cup wall, a rigid disk overlying said flexible strip and having a central aperture, a hemispherical bulb having its rim resting on said rigid disk with its periphery engaging the inner surface of said cup wall, means clamping the aforementioned members in assembled relation, said rigid disk being shaped at its periphery to form an annular chamber, at least one groove in the surface of said rigid disk facing said flexible member and extending between the central aperture of said disk and said annular chamber, an aperture in said cup wall communicating with said chamber, a channel in the face of said flexible disk facing said cup bottom and extending radially thereof, and a passageway leading from said channel through said disk.

9. A dispensing closure according to claim 8 characterized by the flexible disk channel being of rectangular cross-section when the disk is not subjected to pressure.

10. A dispensing closure comprising a disk of flexible material having an aperture, a cup having its bottom outer face contacting said flexible disk and having a bottom aperture alined with said flexible disk aperture, said cup having its bottom inner face slightly concave, a flexible strip overlying said bottom inner face, said strip being of less width than said concave portion and being of proper length and end configuration to conform to the inner surface of said cup wall, a rigid disk overlying said flexible strip and having a central aperture, a hemispherical bulb having its rim resting on said rigid disk with its periphery engaging the inner surface of said cup wall, a circular band enclosing and clamping the aforementioned members in assembled relation, said band having a radially offset portion containing an opening, said rigid disk being chamfered at its periphery to form a pair of annular chambers, grooves in both faces of said rigid disk extending between its central aperture and said annular chambers, a recess in the inner surface of said cup wall communicating with both said chambers, an aperture leading from said recess through said cup wall in alinement with said band opening, said cup bottom and said flexible disk being properly chamfered to form a chamber communicating with the interior of said band-offset portion, a channel in the face of said flexible disk facing said cup bottom and extending radially thereof, and a passageway leading from said channel through said disk.

11. A device of the character described comprising a cup having an apertured extension leading from the bottom thereof, a disk of flexible

material having a passageway receiving said extension with the opposed surfaces of said cup bottom and disk in contact, means clamping together said disk and cup, a channel in the face of said flexible disk facing said cup bottom and extending radially thereof, and a passageway leading from the inner end of said channel through said disk.

12. A device according to claim 11 characterized by said channel being of rectangular cross-section when the disk is not subjected to compression.

13. A dispensing closure comprising a disk of flexible material having an aperture, a cup having its bottom face contacting said flexible disk and having a bottom aperture alined with said flexible disk aperture, an aperture through the cup wall, a hemispherical bulb fitting into said cup, a band enclosing and clamping together said bulb and cup and flexible disk and having an opening alined with said cup wall aperture, a radial channel in the surface of the flexible disk facing the cup bottom, a passageway leading from the inner end of said channel through said flexible disk, a passageway providing communication between the outer end of said channel and said band opening, and means for effecting flow of liquid through the cup bottom and flexible disk apertures into said bulb and discharge therefrom in dispersed condition through said wall aperture and band opening upon alternate expansion and contraction of said bulb.

14. A dispensing closure according to claim 13 characterized by said flexible disk channel being of rectangular cross-section when the disk is not subjected to compression.

15. A dispensing closure comprising a cup having a central bottom aperture, said cup having its bottom inner face slightly concave, a flexible strip overlying said cup bottom, said strip being of less width than the diameter of said concave portion and being of proper length and end configuration to conform to the inner surface of the cup wall, a rigid disk overlying said flexible strip and having a central aperture, a hemispherical bulb having its rim resting on said disk with its periphery contacting the inner surface of the cup wall, means clamping the aforementioned members in assembled relation, said disk being chamfered at its periphery to form a pair of annular chambers, a recess in the inner surface of the cup wall communicating with both said chambers, an aperture leading from said recess through said cup wall, and grooves in both faces of said disk extending between its central aperture and said annular chambers, said grooves being so arranged as to cause fluid flow in opposite directions through said chambers upon manipulation of said bulb irrespective of which side of the disk faces said flexible strip.

16. A dispensing closure for a container having a neck, said closure comprising a disk of pliable material engaging the end of said neck and having a central aperture and radial channels in its upper face, the periphery of said upper face being chamfered and said disk having an opening therethrough communicating with said channels, a cup having a bottom outer face resting on said pliable disk and having a bottom aperture alined with said pliable disk aperture, said outer cup bottom being chamfered at its periphery forming with said pliable disk chamber a V-shaped passageway, and having its bottom inner face slightly concave, a flexible strip overlying said

cup bottom and being of proper length and shape to conform to the inner surface of the cup wall, a rigid disk resting on said flexible strip having a central aperture and grooves in both faces arranged to cause fluid flow in opposite directions, a hemispherical bulb having its rim resting on said rigid disk while contacting the inner surface of the cup wall, said rigid disk being chamfered on its periphery to form a pair of conduits, apertured means clamping the aforementioned members in assembled relation on the container neck, said cup having a recess in its inner wall surface communicating with both of said conduits and an aperture in the center of said recess leading through said cup wall, 15 the arrangement of said rigid disk and flexible strip in said cup being such that upon manipulation of the bulb fluid is caused to flow in op-

posite directions through said conduits to said cup wall recess and therein swirl prior to its ejection through said recess aperture and clamping means aperture in finally dispersed condition and air flow to and from the interior of said container is conducted through said V-shaped passageway communicating with said clamping means aperture.
